UNITED STATES PATENT OFFICE

ETHAN I. DODDS, OF PULLMAN, ILLINOIS, ASSIGNOR TO THE PULLMAN COMPANY, OF CHICAGO, ILLINOIS, A CORPORATION OF ILLINOIS.

ACTUATING MECHANISM FOR CAR-BRAKES.

No. 821,616.

Specification of Letters Patent.

Patented May 29, 1906.

Application filed September 18, 1905. Serial No. 278,929.

To all whom it may concern:

Be it known that I, ETHAN I. DODDS, a citizen of the United States, residing at Pullman, in the county of Cook and State of Illinois, have invented certain new and useful Improvements in Actuating Mechanisms for Car-Brakes, of which the following is a specification.

To provide a brake-operating mechanism which shall occupy small space, requiring but little, if any, lubrication, and be neatly housed or incased, I have invented a clutch and coöperating parts suitable for such purpose, the clutch mechanism being within an integral casing on the brake-handle.

In the accompanying drawings I have illustrated one embodiment of my invention, like reference characters on all the figures referring to the same parts.

Figure 1 is an elevation of my improved brake-actuating mechanism, partly in section. Fig. 2 is a section of the device illustrated in Fig. 1 on the line 2 2 as viewed in the direction indicated by the arrows. Fig. 3 is a section of the device shown in Fig. 1 on line 3 3 as viewed in the direction indicated by the arrows; and Fig. 4 is a perspective view, on an enlarged scale, of a portion of the parts constituting the actuating mechanism.

10 designates the usual vertical brake-shaft, which is rotatably mounted in the car-platform 11 and in a brace or bracket 12, a brake-shoe-operating chain 13 being secured to the lower end of the shaft and adapted to be wound around the shaft as the latter is turned. Just above the platform or floor 11 the shaft 10 is supplied with the usual ratchet-wheel 14 and detent dog or pawl 15, the latter being pivoted at 16. The upper end of the shaft is shouldered at 17, Fig. 4, the extreme upper end of the shaft being threaded at 18, and the shaft being also provided with a keyway 19 for a portion of its length. The brake-handle 20 has at its inner end an integral cylindrical casing 21, having a top 22 with a central aperture 23, the under side of said top being provided with radially-extending teeth 24. The mouth of the casing at its lower end is internally threaded, as shown at 25, while an inwardly-projecting key or feather 26 extends longitudinally of the interior of the casing, as shown in Figs. 1 and 4. At 27 the inner wall of the casing or

housing is supplied with a semicylindrical threaded recess. A disk 28, having a threaded periphery 29, is adapted to enter the lower end of the casing, closing the entrance to the same through screw-threaded engagement with the threads 25. Teeth 30, similar to those on the top wall of the casing, are provided on the upper surface of the disk 28, while a cylindrical boss or sleeve 31 projects from the other side of the latter, said disk being centrally apertured in line with the bore of said sleeve, whereby it is mounted on the shaft 10. When the disk 28 has been screwed into the mouth of the casing, a short screw 45, Fig. 1, is inserted in the internally-threaded hole formed by the semicylindrical recess 27 and a similar registering recess 32 on the periphery of the disk 28, acting as a key to prevent the latter from unscrewing and positioning the teeth 30 opposite the teeth 24.

Between the member 28 and the top of the handle-casing 21 are placed two cam-disks 33 and a plurality of friction-disks 34 and 35, each cam-disk 33 being supplied on one face with a plurality of cam-teeth 36, which coöperate with the projections or teeth 24 and 30. Each cam-disk has a central circular aperture 37, adapted to fit the shaft 10, and a notch 38 in its periphery loosely engaging the key 26 with capacity for a limited play laterally of the latter. Any number of friction-disks 34 and 35 may be used, although I have shown but one of each in Fig. 4, while in Fig. 1 I have illustrated four of the former and three of the latter. Disks 35 are centrally apertured at 39, so as to fit the shaft, and each has a recess 40 in its edge which slidingly engages the key 26, but without lateral play. The cylindrical friction-disks 34 have each a circular central aperture 41 to fit the shaft and also an inwardly-projecting key 42 to engage the keyway 19 of the shaft. It will be seen from this that the friction-disks 35 turn with the handle, the friction-disks 34 turn with the shaft, and the cam members 33 turn with the handle, with which they have, however, a loose or lost-motion rotative engagement.

When all the parts are in place, the top 22 of the handle-casing engages the shoulder 17 of the shaft, being held thereagainst by a nut 43 engaging the threaded end of the shaft,

and pin 44 to prevent its becoming loose. The member 28 is screwed into the mouth of the casing and keyed therein by the small screw 45. The teeth 30 of the member 28 5 coöperate with the downwardly-extended cam-teeth 36 of the lower cam member 33, and the teeth 24 of the casing coact with the upwardly-projecting cam-teeth 36 of the upper cam-disk 33. Between the two members 10 33 are the plurality of friction-disks 34 and 35, the former of which turn on the shaft, while the latter turn with the casing-handle.

The operation of the device is as follows: With the parts assembled, as above described, when the handle 20 is turned in a clockwise direction the teeth 24 and 30 ride over the inclined sides of the cam members 33 to the extent permitted by the lost-motion play of the notches 38 relatively to the 15 key 26, this being sufficient to squeeze the friction-disks together sufficiently to effect a holding engagement between the handle and shaft, after which on a continued rotation of the handle the parts all turn together. During 20 the initial forward movement of the handle the friction between the cam-disks 33 and the adjacent friction-disks is sufficient to prevent the cam-disks from rotating as the teeth 24 and 30 ride up the inclined sides of the 25 cam-teeth pressing the cams toward each other. When it is desired to retract the handle to secure a more favorable position for its operation, it is rotated contra-clockwise, and owing to the lost motion between the handle- 30 casing and the cam-disks 33 the teeth 24 and 30 can slide down the cam-surface sufficiently to release the frictional engagement between the friction-disks, thus permitting the cam-disks and the friction-disks 35 to turn backward, while the friction-disks 34 remain fixed 35 relatively to the shaft, the pawl and ratchet 15 and 14 meanwhile holding the shaft against backward turning.

My invention is not limited to the details 40 of construction described above, and for that reason it is not restricted to the specific features shown and described except to the extent that they are made the subject-matter of specific claims.

50 This patent is intended to embrace only so much of the disclosure made herein as is covered by the claims.

I claim—

1. In a device of the character described, 55 the combination of a shaft, a handle therefor, coöoperating friction devices carried by said shaft and handle, respectively, and means for forcing said friction devices into holding engagement as said handle is turned, 60 substantially as described.

2. In a device of the character described, 65 the combination of a shaft, a rotatable handle therefor, friction devices non-rotatable relatively to said handle and shaft, respectively, and means for forcing said friction de-

vices into holding engagement on the forward movement of said handle, substantially as described.

3. In a device of the character described, 70 the combination of a brake-shaft, a rotatable handle therefor, friction devices non-rotatable relatively to said handle and shaft, respectively, means for forcing said friction devices into holding engagement on the forward movement of said handle, and means to 75 prevent backward movement of said brake-shaft, substantially as described.

4. In a device of the character described, 80 the combination of a shaft, one or more friction-disks movable with said shaft, a shaft-operating device, one or more friction-disks movable with said shaft-operating device, and means serving to force said friction-disks together to secure an operative frictional connection between said shaft-operating device 85 and shaft as the former is actuated, substantially as described.

5. In a device of the character described, 90 the combination of a brake-shaft, one or more friction-disks movable with said shaft, a rotatable brake-handle, one or more friction-disks movable with said brake-handle, means serving to force said friction-disks together to 95 secure an operative frictional connection between said handle and shaft as the former is turned forwardly, and means to prevent backward turning of said shaft, substantially as described.

6. In a device of the character described, 100 the combination of a brake-shaft, a rotatable brake-handle, friction devices movable with said shaft, other friction devices movable with said handle, cam devices serving to force said friction devices into holding engagement with each other as said handle is turned forwardly, and means to prevent backward turning movement of said shaft, substantially as described.

7. In a device of the character described, 110 the combination of a shaft, one or more friction-disks movable with said shaft, a handle, one or more friction-disks movable with said handle, and cam devices operative upon a forward turning movement of said handle to force said friction-disks together and secure 115 an operative frictional connection between said handle and shaft, substantially as described.

8. In a device of the character described, 120 the combination of a brake-shaft, one or more friction-disks movable with said brake-shaft, a rotatable brake-handle, one or more friction-disks movable with said handle, cam devices serving to force said friction-disks together as said handle is turned forwardly, and means to prevent backward movement of 125 said shaft, substantially as described.

9. In a device of the character described, 130 the combination of a shaft, operating means therefor, a friction device movable with said

shaft, a friction device movable with said operating means, a cam slidable on said shaft, and means actuated by said shaft-operating means coöperating with said cam to force said friction devices into holding engagement with each other, substantially as described.

10. In a device of the character described, the combination of a brake-shaft, a rotatable brake-handle, a friction device movable with said brake-shaft, a friction device movable with said brake-handle, a cam slidable on said shaft, means on said handle coöperating with said cam to force said friction devices together as the handle is turned forwardly, and means to prevent backward movement of said shaft, substantially as described.

11. In a device of the character described, the combination of a shaft, a shaft-operating means, a friction device movable with said shaft, a friction device movable with said shaft-operating means, a cam slidable on said shaft and having a lost-motion connection with said operating means, and means actuated by said operating means coöperating with said cam to force said friction devices together on the forward turning movement of said shaft-operating means, substantially as described.

12. In a device of the character described, the combination of a brake-shaft, a rotatable handle therefor, one or more friction-disks movable with said shaft, one or more friction-disks movable with said handle, a cam slid- able with said shaft and having a lost-motion connection with said handle, means actu-

ated by said handle coacting with said cam when said handle is turned forwardly to force said friction-disks together, and means to prevent backward movement of said shaft, substantially as described.

13. In a device of the character described, the combination of a shaft, a handle therefor, one or more friction-disks movable with said shaft, one or more friction-disks movable with said handle, a disk slidably mounted on said shaft and provided with a cam-surface, and a projection on said handle adapted, on the forward movement of the handle, to override said cam-surface and force said friction-disks into holding engagement with each other, substantially as described.

14. In a device of the character described, the combination of a brake-shaft, a rotatable brake-handle, one or more friction-disks movable with said shaft, one or more friction-disks movable with said handle, a pair of disks having cam-surfaces slidably mounted on said shaft above and below said friction-disks, respectively, projections on said handle adapted to override said cam-surfaces and thereby force said disks upon said friction-disks on the forward movement of said handle, and means to prevent backward rotation of said shaft, substantially as described.
